Primary Examiner — John Windmuller*Assistant Examiner* — Steven Czyz(74) *Attorney, Agent, or Firm* — Trego, Hines & Ladenheim, PLLC; Brandon Trego; Jonathan Hines(57) **CLAIM**

I claim the ornamental design for a walking stick holder, as shown and described.

DESCRIPTION

FIG. 1 is a perspective view of a walking stick holder, showing my new design;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.
